TUNABLE ULTRA HIGH FREQUENCY APPARATUS

Leonard R. Malling, Douglaston, N. Y., assignor, by mesne assignments, to Hazeltine Research, Inc., Chicago, Ill., a corporation of Illinois

Application September 25, 1943, Serial No. 503,766

13 Claims. (Cl. 250—36)

1

This invention relates to a tunable ultra-high-frequency apparatus including a plurality of effectively resonant transmission lines tunable over given ranges of operating frequencies in a manner which maintains a predetermined constant relation between their individual operating frequencies. Although the invention is subject to a wide range of applications, it is especially suited for use in an ultra-high-frequency oscillation generator of the directly heated cathode type and will be described in such connection.

In oscillation generators of the directly heated cathode type, the heater circuit forms part of both the anode-cathode and grid-cathode circuits. For low-frequency operation where the heater circuit is primarily resistive, this arrangement is satisfactory. However, in the ultra-high-frequency range the distributed inductance and capacitance of the leads which connect a suitable heater voltage to the cathode cause the heater circuit to be reactive at all except its resonant frequency. For any operating condition in which the heater circuit is primarily reactive, an undesirable phase shift is introduced into the feed-back circuit of the oscillator, impairing its operating efficiency and in severe cases blocking completely the generation of oscillations. For this reason oscillation generators of the type under consideration have a limited operating frequency range unless some provision is made for compensating or avoiding the reactive effects of the heater circuit.

In prior art arrangements a short-circuited effectively resonant transmission line is frequently included in the heater circuit to avoid its aforementioned undesirable reactive effects. The line usually is tuned to have an effective electrical length equal to a half wave length corresponding to the oscillator operating frequency and, therefore, is primarily resistive, exhibiting the properties of a series-resonant circuit. Where the frequency-determining circuit of the generator comprises a second short-circuited effectively resonant transmission line, which is the usual case, the second line also generally has distributed circuit constants, but has an effective electrical length equal to a quarter wave length corresponding to the operating frequency of the oscillator. Since the lines have different effective electrical lengths, the movements of their respective short-circuiting elements to effect identical changes in the operating frequencies of the lines are dissimilar. This is an undesirable limitation of such prior art arrangements in that it precludes the use of a simple unicontrol mechanism for tuning the oscillator over its range of operating frequencies.

2

It is an object of the invention, therefore, to provide an improved tunable ultra-high-frequency apparatus including a plurality of effectively resonant transmission lines and which avoids the aforementioned limitations of prior art arrangements.

It is another object of the invention to provide an improved tunable ultra-high-frequency apparatus comprising a plurality of tunable effectively resonant transmission lines of different effective electrical lengths and having a simplified unicontrol mechanism for tuning the apparatus over a given range of operating frequencies.

In accordance with the invention, a tunable ultra-high-frequency apparatus comprises a first effectively resonant transmission line having an effective electrical length equal to an integral multiple of a quarter wave length corresponding to a predetermined operating frequency. This first line includes adjustable tuning means for varying its effective electrical length to tune the line over a given range of operating frequencies. The apparatus also comprises a second effectively resonant transmission line uniformly loaded throughout at least a portion of its length and having an effective electrical length equal to an integral multiple of a quarter wave length corresponding to a predetermined operating frequency. The second line also includes adjustable tuning means in the uniformly loaded portion thereof for varying its effective electrical length to tune the second line over a given range of operating frequencies and unicontrol means are provided for effecting substantially identical physical adjustments of the tuning means of the first and second lines. Additionally, the loading of the second line is such that a predetermined constant relation is maintained between the operating frequencies of the first and second lines as these lines are tuned over their ranges of operating frequencies.

As employed throughout this specification and in the appended claims, the term "effectively resonant transmission line" refers to a transmission line and its terminating impedance which together exhibit certain desirable characteristics at or near its resonant frequency, which frequency is determined by the distributed parameters of the line and its terminating impedance.

For a better understanding of the present invention, together with other and further objects thereof, reference is had to the following description taken in connection with the accompanying drawing, and its scope will be pointed out in the appended claims.

In the drawing, Fig. 1 is a perspective view, partially schematic, of a tunable ultra-high-frequency apparatus embodying the present invention in a preferred form; Fig. 2 is a schematic circuit diagram which is the electrical equivalent of the circuit of Fig. 1; and Fig. 3 is a fragmentary perspective view of a portion of the apparatus of Fig. 1 in modified form.

Referring now more particularly to Fig. 1, there is represented a tunable ultra-high-frequency apparatus, specifically an oscillation generator of the directly heated cathode type, operable over a given range of operating frequencies and embodying the present invention. The apparatus comprises a vacuum-tube oscillator 10, represented schematically, having an anode, a control electrode, and a directly heated cathode, and a frequency-determining circuit provided by a first effectively resonant transmission line 11 directly connected to the anode and control electrode of the vacuum tube so as to be terminated by their interelectrode capacitance C_{g-p} . Transmission line 11 has an effective electrical length equal to an odd integral multiple of a quarter wave length corresponding to a predetermined operating frequency, the integer for the illustrated embodiment preferably being equal to one. Thus, the effective electrical length of the line 11 equals a quarter wave length corresponding to the operating frequency of the oscillation generator. This transmission line includes a pair of horizontally disposed parallel conductors 12 and 13 of uniformly distributed inductance and capacitance and an adjustable tuning means, comprising a short-circuiting member, for varying their effective electrical length to tune the line over a given range of operating frequencies determined by the desired operating frequency range of the apparatus. Conductors 12 and 13 are supported in but insulated from extensions of the end walls of a metal container 30, the line insulators being omitted in order to simplify the drawing. The short-circuiting member for varying their effective electrical length consists of conductive elements 14 and 15 secured to the horizontal portion of a supporting yoke 16 of suitable insulating material, such as a thermoplastic resin. Elements 14 and 15 are individually apertured to receive and be freely movable along conductors 12 and 13. A mica strip 17 is positioned intermediate the adjacent ends of elements 14 and 15 effectively to constitute the described short-circuiting member a condenser which completes the circuit of line 11 for alternating currents. A condenser 18 is bridged across those terminals of conductors 12 and 13 which are remote to tube 10 for the purpose of detuning that portion of line 11 located between such remote terminals and short-circuiting member 14-15-17.

The cathode of vacuum tube 10 is heated by means of a suitable battery, indicated A, through a heater circuit that includes a second effectively resonant transmission line 20 uniformly loaded throughout at least a portion of its length and having an effective electrical length equal to an even integral multiple of a quarter wave length corresponding to a predetermined operating frequency. For the embodiment under consideration, transmission line 20 is loaded throughout a major portion of its length by dielectric means, in a manner described more particularly hereinafter, and has an effective electrical length equal to a half wave length corresponding to the operating frequency of the oscillator. This transmission line similarly comprises a pair of par-

allel conductors 21 and 22, a short-circuiting member including conductive elements 23 and 24, an interposed strip of mica 25, and a detuning condenser 28 connected across the ends of conductors 21 and 22 which are remote to tube 10. These elements have the same construction as corresponding elements of transmission line 11. Also, line 20 is supported in, but insulated from, the end walls of container 30 through insulating bushings (not shown). Short-circuiting member 23-24-25 is grounded to the metal container 30 through a resilient U-shaped brush 29 which is adapted to engage a side wall of the container and be freely slideable therealong.

In general, the terminating impedance of line 20 provided by the impedance of the cathode of tube 10 is materially different from the terminating impedance of line 11. As a consequence, it is necessary to displace the short-circuiting members of the lines, as indicated by the dimension line d in the drawing, to have the lines tuned to the same operating frequency. For this purpose short-circuiting member 23-24-25 of line 20 is adjustably secured to supporting yoke 16 through an insulated U-shaped member 26 having elongated slots 27.

Uniform loading of line 20 throughout a major portion of its length is accomplished by immersing that portion thereof in a homogeneous dielectric material. To this end, that portion of line 20 is supported within the container 30, the container being filled with a liquid dielectric, such as oil, to such a depth, indicated by broken line 31 in the drawing, that the portion of line 20 contained therein is completely immersed. The oil utilized is chosen to have such a dielectric constant that equal incremental displacements of shorting bars 14-15-17 and 23-24-25 along lines 11 and 20, respectively, cause such variations in the operating frequencies of the lines that a predetermined constant relation is maintained between the operating frequencies of the lines as they are tuned over their individual operating frequency ranges. For the described embodiment of the invention, the dielectric is chosen of such value that identical changes are effected in the operating frequencies of lines 11 and 20 for equal physical adjustments of their individual short-circuiting members.

The apparatus further comprises unicontrol means for effecting substantially identical physical adjustments of the tuning means of lines 11 and 20. Such unicontrol means consists of a threaded rod 33 engaging a threaded aperture in yoke 16 and suitably supported in end walls of container 30. The rod 33 is terminated in a knurled knob 36 which facilitates precise adjustment of yoke 16 and exact tuning of the apparatus. A grid-leak resistor 32 is coupled to the control electrode of vacuum tube 10 through conductor 12 and a source of space current indicated +B is coupled to the anode thereof through conductor 13.

In considering the operation of the described arrangement, it will be seen that, for a given operating condition, transmission line 20 has an effective electrical length equal to a half wave length corresponding to the instant operating frequency of the oscillation generator. It is well known in transmission network theory that a short-circuited effectively resonant transmission line having such an effective electrical length exhibits impedance characteristics analogous to those of a series-resonant circuit, that is, it has zero series impedance at the resonant frequency.

Therefore, subject to the usual assumptions that the resistance of the cathode element and transmission line 20 is negligible, the cathode is effectively at ground potential. Accordingly, the oscillation generator is of the type represented schematically in Fig. 2, wherein the distributed inductance of conductors 12 and 13 of transmission line 11 is represented by the lumped inductances L_2 and L_1 , respectively, and the inter-electrode capacitance C_{g-p} and the distributed capacitance of line 11 are represented by the lumped capacitance C . Capacitor C_{17} , a blocking condenser, is comprised of the elements 14-15-17 as hereinbefore described. The oscillating circuit of Fig. 2 is generally similar to the well-known Hartley type oscillator, the operation of which is well understood in the art.

For tuning the oscillation generator, the inductance and capacitance of its frequency-determining circuit are variable, as represented in Fig. 2, through the movement of short-circuiting member 14-15-17. However, adjustment of unicontrol means 33 to effect such movement of short-circuiting member 14-15-17 produces corresponding and equal displacements of short-circuiting member 23-24-25. Thus, it will be seen that, by virtue of its selected uniform loading which is different from that of line 11, line 20 is tuned to substantially the same frequency as line 11 and, therefore, to the operating frequency of the oscillation generator as the generator is tuned throughout its range of operating frequencies. In other words, the circuit diagram of Fig. 2 represents the equivalent circuit of the generator for any tuning condition. Hence, the cathode of tube 10 is effectively maintained at ground potential for all operating conditions, thereby to ensure maximum oscillator efficiency.

While applicant does not intend to limit the invention to any specific circuit constants, the following are given for the purposes of illustration:

Tube 10	Type 368-A
Conductors 12, 13, 21, and 22	1/8" rod 6" long separated 1/4"
Condenser C_{17} and condenser C_{24}	100 micro-microfarads each
Condenser C_{18} and condenser C_{28}	250 micro-microfarads each
Distance d	1 centimeter
Loading material and its dielectric constant	Castor oil-4.6
Frequency range	500-1500 megacycles

Reference is now made to Fig. 3 which illustrates a modified form of the invention. The modification includes a pair of effectively resonant transmission lines similar to those of Fig. 1, corresponding components thereof having identical reference numerals primed. For the purpose of simplicity, only a portion of the lines is represented, but it will be understood that their construction and arrangement may be the same as those of Fig. 1. Loading of line 20' is achieved through reactance means comprising a plurality of substantially identical capacitors 40 uniformly spaced along the line. Loading capacitors 40 are selected of such value as to maintain a predetermined constant relation between the operating frequencies of lines 11' and 20' as the lines are tuned over their ranges of operating frequencies in a manner particularly de-

scribed with reference to the loading of line 20 in the Fig. 1 arrangement. The tuning arrangement of Fig. 3 may be substituted for that of Fig. 1 in which case condensers 40 are selected to maintain lines 11' and 20' at the same operating frequencies as the oscillation generator is tuned over its operating frequency range.

In the preferred embodiment of the invention, short-circuiting members 14-15-17 and 23-24-25 are displaced with reference to one another to compensate for the dissimilar terminating impedances of lines 11 and 20. However, it will be understood that a compensating impedance may be shunted across the open end of line 20 to cause the line terminations to be substantially identical. In that case, the shorting bars 14-15-17 and 23-24-25 may be in vertical alignment, simplifying the construction of supporting members 16 and 26.

It will be understood that the transmission lines 11 and 20 may take the form of coaxial lines. In this case, uniform loading of one of the lines may be accomplished by filling a portion thereof with a liquid dielectric material, such as oil.

While in the described embodiment of the invention, it is desirable so to load one of the transmission lines that the first and second lines have the same operating frequencies, it will be understood that this frequency relationship is an illustrative but not exclusive one. In some applications, for example in the case of an oscillator-modulator operable over a predetermined range of frequencies in the ultra-high-frequency spectrum, the invention may be utilized to maintain a predetermined constant frequency difference between the operating frequencies of two effectively resonant transmission lines.

Also, it is well known that a short-circuited effectively resonant transmission line having an effective electrical length equal to a quarter wave length corresponding to a predetermined operating frequency exhibits the same impedance characteristics as an open-circuited effectively resonant transmission line having an effective electrical length equal to a half wave length corresponding to such operating frequency. Likewise, a short-circuited effectively resonant transmission line having an effective electrical length equal to a half wave length of a predetermined operating frequency presents the same impedance characteristics as an open-circuited effectively resonant transmission line having an effective electrical length equal to a quarter wave length of such operating frequency. Such equivalent lines may be utilized in a tunable ultra-high-frequency apparatus in accordance with the invention so long as one line is appropriately loaded in the manner hereinbefore described.

While there have been described what are at present considered to be the preferred embodiments of this invention, it will be obvious to those skilled in the art that various changes and modifications may be made therein without departing from the invention, and it is, therefore, aimed in the appended claims to cover all such changes and modifications as fall within the true spirit and scope of the invention.

70 What is claimed is:

1. A tunable ultra-high-frequency apparatus comprising, a first effectively resonant transmission line having an effective electrical length equal to an integral multiple of a quarter wave length corresponding to a predetermined operat-

ing frequency, said first line including adjustable tuning means for varying its effective electrical length to tune said line over a given range of operating frequencies, a second effectively resonant transmission line uniformly loaded throughout at least a portion of its length and having an effective electrical length equal to an integral multiple of a quarter wave length corresponding to a predetermined operating frequency, said second line including adjustable tuning means in said uniformly loaded portion thereof for varying its effective electrical length to tune said second line over a given range of operating frequencies, and unicontrol means for effecting substantially identical physical adjustments of said tuning means of said first and second lines, said loading of said second line being such that a predetermined constant relation is maintained between the operating frequencies of said first and second lines as said lines are tuned over said ranges of operating frequencies.

2. A tunable ultra-high-frequency apparatus comprising, a first short-circuited effectively resonant transmission line having an effective electrical length equal to an integral multiple of a quarter wave length corresponding to a predetermined operating frequency, said first line including adjustable tuning means for varying its effective electrical length to tune said line over a given range of operating frequencies, a second effectively resonant transmission line uniformly loaded throughout at least a portion of its length and having an effective electrical length equal to an integral multiple of a quarter wave length corresponding to a predetermined operating frequency, said second line including adjustable tuning means in said uniformly loaded portion thereof for varying its effective electrical length to tune said second line over a given range of operating frequencies, and unicontrol means for effecting substantially identical physical adjustments of said tuning means of said first and second lines, said loading of said second line being such that a predetermined constant relation is maintained between the operating frequencies of said first and second lines as said lines are tuned over said ranges of operating frequencies.

3. A tunable ultra-high-frequency apparatus comprising, a first effectively resonant transmission line having an effective electrical length equal to an integral multiple of a quarter wave length corresponding to a predetermined operating frequency, said first line including adjustable tuning means for varying its effective electrical length to tune said line over a given range of operating frequencies, a second short-circuited effectively resonant transmission line uniformly loaded throughout at least a portion of its length and having an effective electrical length equal to an integral multiple of a quarter wave length corresponding to a predetermined operating frequency, said second line including adjustable tuning means in said uniformly loaded portion thereof for varying its effective electrical length to tune said second line over a given range of operating frequencies, and unicontrol means for effecting substantially identical physical adjustments of said tuning means of said first and second lines, said loading of said second line being such that a predetermined constant relation is maintained between the operating frequencies of said first and second lines as said lines are tuned over said ranges of operating frequencies.

4. A tunable ultra-high-frequency apparatus

comprising, a first effectively resonant transmission line including a pair of parallel conductors and having an effective electrical length equal to an integral multiple of a quarter wave length corresponding to a predetermined operating frequency, said first line including short-circuiting means movable along said conductors for varying the effective electrical length of said line to tune said line over a given range of operating frequencies, a second effectively resonant transmission line including a pair of parallel conductors uniformly loaded throughout at least a portion of their length and having an effective electrical length equal to an integral multiple of a quarter wave length corresponding to a predetermined operating frequency, said second line including short-circuiting means movable along said loaded portion of said conductors for varying the effective electrical length of said second line to tune said second line over a given range of operating frequencies, and unicontrol means for effecting substantially identical physical adjustments of said short-circuiting means of said first and second lines, said loading of said second line being such that a predetermined constant relation is maintained between the operating frequencies of said first and second lines as said lines are tuned over said ranges of operating frequencies.

5. A tunable ultra-high-frequency apparatus comprising, a first effectively resonant transmission line having an effective electrical length equal to an integral multiple of a quarter wave length corresponding to a predetermined operating frequency, said first line including adjustable tuning means for varying its effective electrical length to tune said line over a given range of operating frequencies, a second effectively resonant transmission line uniformly loaded throughout at least a portion of its length and having an effective electrical length equal to an integral multiple of a quarter wave length different from that of the first effectively resonant transmission line corresponding to said predetermined operating frequency, said second line including adjustable tuning means for varying its effective electrical length to tune said second line over said range of operating frequencies, and unicontrol means for effecting substantially identical physical adjustments of said tuning means of said first and second lines, said loading of said second line being such that the operating frequencies of said first and second lines are maintained substantially equal as said lines are tuned over said range of operating frequencies.

6. A tunable ultra-high-frequency apparatus comprising, a first effectively resonant transmission line having an effective electrical length equal to a quarter wave length corresponding to a predetermined operating frequency, said first line including adjustable tuning means for varying its effective electrical length to tune said line over a given range of operating frequencies, a second effectively resonant transmission line uniformly loaded throughout at least a portion of its length and having an effective electrical length equal to a half wave length corresponding to a predetermined operating frequency, said second line including adjustable tuning means in said uniformly loaded portion thereof for varying its effective electrical length to tune said second line over a given range of operating frequencies, and unicontrol means for effecting substantially identical physical adjustments of said tuning means of said first and second lines, said loading of said second line being such that a predetermined con-

stant relation is maintained between the operating frequencies of said first and second lines as said lines are tuned over said ranges of operating frequencies.

7. A tunable ultra-high-frequency apparatus comprising, a first effectively resonant transmission line having an effective electrical length equal to an odd integral multiple of a quarter wave length corresponding to a predetermined operating frequency, said first line including adjustable tuning means for varying its effective electrical length to tune said line over a given range of operating frequencies, a second effectively resonant transmission line uniformly loaded throughout at least a portion of its length and having an effective electrical length equal to an even integral multiple of a quarter wave length corresponding to a predetermined operating frequency, said second line including adjustable tuning means in said uniformly loaded portion thereof for varying its effective electrical length to tune said second line over a given range of operating frequencies, and unicontrol means for effecting substantially identical physical adjustments of said tuning means of said first and second lines, said loading of said second line being such that a predetermined constant relation is maintained between the operating frequencies of said first and second lines as said lines are tuned over said ranges of operating frequencies.

8. A tunable ultra-high-frequency apparatus comprising, a first effectively resonant transmission line having an effective electrical length equal to an integral multiple of a quarter wave length corresponding to a predetermined operating frequency, said first line including adjustable tuning means for varying its effective electrical length to tune said line over a given range of operating frequencies, a second effectively resonant transmission line, dielectric means for uniformly loading said second line throughout at least a portion of its length to cause said line to have an effective electrical length equal to an integral multiple of a quarter wave length corresponding to a predetermined operating frequency, said second line including adjustable tuning means in said uniformly loaded portion thereof for varying its effective electrical length to tune said second line over a given range of operating frequencies, and unicontrol means for effecting substantially identical physical adjustments of said tuning means of said first and second lines, said loading of said second line being such that a predetermined constant relation is maintained between the operating frequencies of said first and second lines as said lines are tuned over said ranges of operating frequencies.

9. A tunable ultra-high-frequency apparatus comprising, a first effectively resonant transmission line having an effective electrical length equal to an integral multiple of a quarter wave length corresponding to a predetermined operating frequency, said first line including adjustable tuning means for varying its effective electrical length to tune said line over a given range of operating frequencies, a second effectively resonant transmission line comprising a pair of spaced parallel conductors, a homogeneous dielectric material in the space between said conductors throughout at least a portion of their length for uniformly loading said second line to cause said second line to have an effective electrical length equal to an integral multiple of a quarter wave length corresponding to a predetermined operating frequency, said second line in-

cluding adjustable tuning means in said uniformly loaded portion thereof for varying its effective electrical length to tune said second line over a given range of operating frequencies, and unicontrol means for effecting substantially identical physical adjustments of said tuning means of said first and second lines, said loading of said second line being such that a predetermined constant relation is maintained between the operating frequencies of said first and second lines as said lines are tuned over said ranges of operating frequencies.

10. A tunable ultra-high-frequency apparatus comprising, a first effectively resonant transmission line having an effective electrical length equal to an integral multiple of a quarter wave length corresponding to a predetermined operating frequency, said first line including adjustable tuning means for varying its effective electrical length to tune said line over a given range of operating frequencies, a second effectively resonant transmission line including reactance means for uniformly loading said line throughout at least a portion of its length and having an effective electrical length equal to an integral multiple of a quarter wave length corresponding to a predetermined operating frequency, said second line including adjustable tuning means in said uniformly loaded portion thereof for varying its effective electrical length to tune said second line over a given range of operating frequencies, and unicontrol means for effecting substantially identical physical adjustments of said tuning means of said first and second lines, said loading of said second line being such that a predetermined constant relation is maintained between the operating frequencies of said first and second lines as said lines are tuned over said ranges of operating frequencies.

11. A tunable ultra-high-frequency apparatus comprising, a first effectively resonant transmission line having an effective electrical length equal to an integral multiple of a quarter wave length corresponding to a predetermined operating frequency, said first line including adjustable tuning means for varying its effective electrical length to tune said line over a given range of operating frequencies, a second effectively resonant transmission line including a plurality of substantially identical and uniformly spaced capacitors for uniformly loading said second line throughout at least a portion of its length and having an effective electrical length equal to an integral multiple of a quarter wave length corresponding to a predetermined operating frequency, said second line including adjustable tuning means in said uniformly loaded portion thereof for varying its effective electrical length to tune said second line over a given range of operating frequencies, and unicontrol means for effecting substantially identical physical adjustments of said tuning means of said first and second lines, said loading of said second line being such that a predetermined constant relation is maintained between the operating frequencies of said first and second lines as said lines are tuned over said ranges of operating frequencies.

12. A tunable ultra-high-frequency apparatus comprising, a vacuum tube having an anode, a control electrode and a directly heated cathode, a first effectively resonant transmission line coupled to said anode and control electrode and having an effective electrical length equal to an integral multiple of a quarter wave length corresponding to a predetermined operating frequency,

11

said first line including adjustable tuning means for varying its effective electrical length to tune said line over a given range of operating frequencies, a heater circuit coupled to said cathode including a second effectively resonant transmission line uniformly loaded throughout at least a portion of its length and having an effective electrical length equal to an integral multiple of a quarter wave length corresponding to a predetermined operating frequency, said second line including adjustable tuning means in said uniformly loaded portion for varying its effective electrical length to tune said second line over a given range of operating frequencies, and unicontrol means for effecting substantially identical physical adjustments of said tuning means of said first and second lines, said loading of said second line being such that a predetermined constant relation is maintained between the operating frequencies of said first and second lines as said lines 20 are tuned over said ranges of operating frequencies.

13. A tunable ultra-high-frequency apparatus comprising, an oscillation generator including a vacuum tube having an anode, a control electrode and a directly heated cathode, a first effectively resonant transmission line coupled to the anode control electrode for determining the frequency of the generated oscillations and having an effective electrical length equal to an integral multiple of a quarter wave length corresponding to a predetermined operating frequency, said first line

12

including adjustable tuning means for varying its effective electrical length to tune said line over a given range of operating frequencies, a heater circuit coupled to said cathode including a second effectively resonant transmission line uniformly loaded throughout at least a portion of its length and having an effective electrical length equal to a different integral multiple of a quarter wave length corresponding to said predetermined operating frequency, said second line including adjustable tuning means in said uniformly loaded portion thereof for varying its effective electrical length to tune said second line over said range of operating frequencies, and unicontrol means for effecting substantially identical physical adjustments of said tuning means of said first and second lines, said loading of said second line being such that the operating frequencies of said first and second lines are maintained substantially equal as said lines are tuned over said ranges of operating frequencies.
